Primary Examiner — Brian N Vinson(74) *Attorney, Agent, or Firm* — Gottlieb, Rackman & Reisman PC(57) **CLAIM**

The ornamental design for a lighting device, as shown and described.

DESCRIPTION

FIG. 1 is a top and front perspective view of a lighting device showing my new design;

FIG. 2 is a top plan view thereof;

FIG. 3 is front elevational view thereof;

FIG. 4 is a rear elevational view thereof;

FIG. 5 is a left side view thereof; and,

FIG. 6 is a right side view thereof.

The broken lines showing the environment in some of the figures are for illustrative purpose only and form no part of the claimed design.
